(57) CLAIM

The ornamental design for a shopping cart frame assembly, as shown and described.

DESCRIPTION

FIG. 1 is a front, right, perspective view of a shopping cart frame according to the present invention, with a shopping cart basket shown in broken lines;

FIG. 2 is a right side view (the left side view being identical to the right side view) of the shopping cart frame as shown in FIG. 1, with a shopping cart basket shown in broken lines;

FIG. 3 is a top view of the shopping cart frame shown in FIG. 1, with a shopping cart basket shown in broken lines;

FIG. 4 is a bottom view of the shopping cart frame shown in FIG. 1, with a shopping cart basket shown in broken lines;

FIG. 5 is a front view of the shopping cart frame shown in FIG. 1, with a shopping cart basket shown in broken lines;

FIG. 6 is a rear view of the shopping cart frame shown in FIG. 1, with a shopping cart basket shown in broken lines; and,

FIG. 7 is a perspective view of the shopping cart frame alone shown in FIG. 1.

The broken line illustration of a shopping cart basket shown in FIGS. 1–6 are only for purposes of showing the environment in which the shopping cart frame of the invention is to be used, and forms no part of the claimed design.
